ADJUSTABLE INDUCTANCE

Fred W. Schmidt, Jr., Cedar Grove, N. J., assignor
to Allen B. Du Mont Laboratories, Inc., Clifton,
N. J., a corporation of Delaware

Application June 20, 1951, Serial No. 232,536

4 Claims. (Cl. 336—138)

1

This invention relates to an adjustable inductance particularly suitable for use in radio and television circuits.

Objects of the invention are to provide an adjustable inductance that is compact, economical to make, and stable. Other objects will be apparent.

In the drawings,

Figure 1 shows a side elevational view of an embodiment of the invention.

Figure 2 shows a cross-sectional view through 2—2 of Figure 1.

Figures 3 and 4 show side elevational and sectional views, respectively, of an alternative embodiment of the invention.

Figure 5 shows a modification of the embodiment of Figure 1.

Referring to Figures 1 and 2, an adjustable inductance 11 is formed from a conductive material such as brass or copper, preferably silver plated, and comprises two parallel inductive leg portions 12 and 13 supported in parallel relationship by a bridging portion 14. A member 16 is threaded through a suitable threaded opening in the bridging portion 14. The end portion 17 of the member 16 makes electrical contact with each of the inductive members 12 and 13. The threaded member 16 may be provided with a slot 18 whereby it may be rotated and made to move axially within the confines of said inductance members 12 and 13. The open ends 21 and 22 of said inductive members 12 and 13, respectively, serve as terminals for connections to an electric circuit.

The inductive path extends from terminal 21 through a portion of the leg member 12, through the end 17 of the threaded member 16, and through a portion of the leg member 13 to the terminal 22. The length of the inductive path may be varied and the inductance accordingly changed by rotating the threaded member 16 so as to change the position of the end portion 17 along the length of the inductive members 12 and 13. The inductive members 12 and 13 are preferably inclined slightly towards one another at the ends 21 and 22 thereof in a resilient manner, so as to provide a gripping action against the threaded member 16. This action serves to provide good electrical connections between the inductive members 12 and 13 and the end portion 17 of the threaded member 16 and also provides mechanical friction so that the threaded member is not easily turned accidentally.

The inductance 11 may be machined from a solid piece of metal. Preferably, the first opera-

2

tion is to drill and tap a threaded hole axially through said material to accommodate the threaded member 16. A slot 23 is then machined longitudinally through the longitudinal hole along a portion of the length of the material, thus providing the inductive leg members 12 and 13 with a longitudinal concave groove along the inner surface of each thereof. The members 12 and 13 may then be bent slightly inwardly toward each other.

The embodiment shown in Figures 3 and 4 may be fabricated from a strip of conductive material so as to form inductive portions 26 and 27 supported by a bridging portion 28; a threaded member 29 is threaded through the bridging portion 28 and along and within the confines of the inductive portions 26 and 27 so that an end portion 31 of the threaded member 29 is in electrical contact with both of said inductive members. Electric circuit connections are made at the outer end portions 32 and 33 of the inductive members 26 and 27, respectively. As described above, the inductive members 26 and 27 preferably provide resilient inward pressures against the end 31 of the threaded member 29 to provide electrical and mechanical contact therewith.

Figure 5 shows a preferred type of terminal connections 36 and 37 attached to the inductive members 12 and 13. The terminals 36 and 37 are projections from and integral with the inductive members, and provide a convenient means for soldering the adjustable inductance to an electrical circuit.

While preferred embodiments have been disclosed, it will be apparent that further embodiments and ramifications thereof may be designed by one skilled in the art. The scope of invention is defined in the following claims.

What is claimed is:

1. An adjustable inductance comprising a plurality of elongated inductive members, a bridging member supporting said inductive members in parallel spaced relationship, and a conductive member threaded through said bridging member and axially between a portion of said elongated inductive members in electrical contact therewith, said threaded member acting by axial movement when turned to change the inductance of said elongated members.
2. An adjustable inductance comprising a pair of parallel spaced elongated inductive members, an adjustment member of conductive material threaded axially and between and in electrical contact with a portion of said inductive members, and circuit connections to said inductive mem-

bers to provide an inductive path through said inductive members and said adjustment member.

3. An adjustable inductance comprising a pair of elongated inductive members positioned in parallel relationship to form a slit therebetween, a longitudinal concave groove in each of said inductive members on the surfaces thereof facing said slit, and an elongated conductive member threaded axially in and along a portion of said grooves and making electrical contact with both of said inductive members.

4. The adjustable inductance in accordance with claim 1, in which said elongated inductive

members are resiliently sprung mutually toward one another at ends thereof remote from said bridging member to insure engagement of said elongated members against the end of said threaded member therebetween.

FRED W. SCHMIDT, JR.
